UNITED STATES PATENT OFFICE.

WILLIAM L. MILLER, OF NEWARK, NEW JERSEY, ASSIGNOR TO HARRY TORCHIANI, OF NEW YORK, N. Y.

BARREL-PITCHING MACHINE.

SPECIFICATION forming part of Letters Patent No. 627,781, dated June 27, 1899.

Application filed February 6, 1899. Serial No. 704,754. (No model.)

To all whom it may concern:

Be it known that I, WILLIAM L. MILLER, a citizen of the United States, residing at Newark, in the county of Essex and State of New Jersey, have invented certain new and useful Improvements in Pitching-Machines, of which the following is a specification.

This invention relates to an improved machine for pitching barrels of that type for which Letters Patent of the United States were granted to Maximilian Guethler under date of December 22, 1896, No. 573,818, in which a pitch-reservoir is suspended within a pitch-kettle and connected by means of valves with a pipe for supplying compressed air whenever the pitch is to be discharged, a valve for supplying melted pitch from the kettle to the reservoir, and means for discharging the air in the pitch-reservoir to the atmosphere before a new supply of pitch is supplied from the kettle to the reservoir.

The object of the present invention is to simplify the construction of the pitching-machines of such class and render them more reliable than heretofore, as the pitch was liable to be carried along into the air-outlet pipes so as to clog up the pipes and make frequent cleaning necessary.

The invention consists of a machine for pitching barrels, which comprises a pitch-kettle, a reservoir suspended within said kettle and divided by a partition, valves for admitting melted pitch from the kettle to the reservoir, a pipe for supplying compressed air to the reservoir, and a four-way valve for opening or closing the compressed-air pipe and permitting the discharge of air from either compartment of the reservoir to the atmosphere.

The invention consists, further, of the special construction of the four-way valve employed, and, lastly, in a guard device located in the air supply and discharge pipe, which prevents the ingress of pitch into said air-pipe, all as will be fully described hereinafter and finally pointed out in the claims.

In the accompanying drawings, Figure 1 represents a vertical central section of my improved machine for pitching barrels. Fig. 2 is a vertical central section, drawn on a larger scale, showing the means for supply-

ing air under pressure to the pitch-chambers, said figure also showing the guard devices for preventing the ingress of pitch into the air-pipes; and Figs. 3, 4, and 5 are horizontal sections through the four-way valve of the air supply and discharge pipes, showing the different positions assumed by the same in shutting off the supply of compressed air or in permitting it to pass to either one of the pitch-chambers for forcing the pitch in the same into the barrels to be pitched.

Similar letters of reference indicate corresponding parts.

Referring to the drawings, A represents a kettle for melting the pitch, which kettle is to be supported in a suitable furnace. The kettle A is provided with a cover A', on which are arranged two or more supports C for the kegs or barrels to be pitched. Within the pitch-kettle A is suitably suspended a closed tank or reservoir D, which is divided by a partition D' into two compartments or chambers D² D³, so that one barrel at a time can be supplied with pitch from one of the compartments.

In the drawings the machine is shown for pitching two barrels alternately; but it is obvious that the machine can also be arranged for pitching four or more barrels, in which case the pitch kettle and reservoir D are made correspondingly larger and divided by an additional partition at right angles to the partition D' into four compartments. In the bottom of each pitch-chamber D² D³ is arranged an opening e or e', which is closed by a clack-valve E. The top of each chamber D² D³ is connected by an air-pipe F with a four-way valve G, which is provided with a port f for the ingress of compressed air and is connected with a compressed-air pipe G² and with two ports f' f' at diametrically opposite points, which are respectively connected with the air-pipes F F, leading to each one of the chambers D² D³, and with an outlet-port which is divided by a partition f³ into two smaller ports f² f², so that both chambers D² D³ can be put in communication with the atmosphere at one and the same time when the spigot G' of the four-way valve G is set in the position shown in Fig. 3, in which position the compressed-air port f is entirely closed and both small ports f² f² are partly open, so that the air can

escape from both chambers D^2 D^3 to the atmosphere.

The plug G' is provided with a spindle, to the upper end of which is applied a lever G^2 5 for operating the valve, said lever being so arranged that it indicates by its position which one of the barrels is being supplied with pitch.

Each compartment or chamber D^2 D^3 is further connected by an outlet-pipe H , which 10 passes from the bottom of the chamber D^2 or D^3 through the cover A' of the pitch-kettle A to a point centrally within the support C for the barrel, said outlet-pipe H being provided with a perforated nozzle, so as to discharge a 15 spray of pitch into the barrel to be pitched. Openings o are arranged in the cover near each outlet-pipe H , so that the surplus pitch that is dropped through the bunghole of the barrel is returned into the pitch-kettle.

20 The valve-plug G' is provided with concave side recesses, so that the horizontal section of the plug within the casing is of the form shown in Figs. 3 to 5—namely, provided with a large segmental portion p at that edge adjacent to the compressed-air port and with a narrow portion p' , but of larger size, however, than either one of the air-outlet ports f^2 and of less size than the larger outlet-port formed by said small ports. This has the advantage 25 that the air can be discharged from both chambers simultaneously when the supply of compressed air is entirely shut off, as in Fig. 3. When the left-hand chamber is filled and ready for discharging its pitch into the keg or 30 barrel, the valve is set in the position shown in Fig. 4, so that the compressed air can act on the pitch in the left-hand compartment D^2 . and force the same through the outlet-pipe H into the keg to be pitched. During the dis- 35 charge of pitch from the chamber D^2 the adjacent chamber D^3 is filling with pitch from the pitch-kettle through opening e by the automatic opening of its bottom valve E , while the air in the same is forced by the rising 40 pitch through the outlet-port f^2 to the atmosphere. When the right-hand chamber D^3 is to discharge its pitch, the valve is moved into the position shown in Fig. 5, in which case the compressed air acts on the pitch in the 45 right-hand chamber D^3 , so as to discharge it into the barrel to be pitched, while the left-hand chamber D^2 communicates with the atmosphere and is ready to be filled with pitch from the pitch-kettle. During the shifting 50 of the plug G' from the position shown in Fig. 4 to that shown in Fig. 5 the compressed-air supply is first shut off by the larger portion p of the spigot, while the narrower portion p' when it has moved to the position 55 shown in Fig. 3 permits the compressed air in the left-hand chamber to puff off to the atmosphere, and the pitch can then enter from the pitch-kettle into the left-hand chamber D^2 . When the valve is turned into position 60 shown in Fig. 5, the air that is forced out by the rising pitch can pass through the outlet- 65 pipe, while the right-hand chamber is dis-

charged for pitching the barrel. By the provision of the large outlet-port, which is divided into two smaller ports by its partition, 70 and of the larger portion p of the plug the latter is adapted to be shifted from its intermediate position (shown in Fig. 3) and the compressed air admitted to either chamber. As the compressed-air port is closed by the 75 said portion p in advance of the opening of the said outlet-port, there will be no shocks or concussions in the apparatus.

In each discharge-pipe F is arranged at its connection with the chambers D^2 D^3 a guard device I , the shank of which is supported in the ends of the air supply and discharge pipe F . The guard devices I are surrounded by casings I' of larger diameter than the pipes F , so that when the compressed air is discharged from either one of the chambers D^2 D^3 no melted pitch can be carried along, as the same is retained by the guard device and returned to the chamber. This prevents the clogging of the pipes F by the melted pitch, 85 as the same is returned partly by the guard device and partly by the casing which extends around the ends of the pipes F , as shown in Fig. 2. This arrangement of the guard device is an important feature, as thereby one 90 of the objectionable features in pitching-machines, which was found out by practical use of the same—namely, the carrying along of melted pitch into the four-way valve by the escaping air under pressure—is entirely avoided, and the air-pipes, as well as the four-way 95 valve, are protected against ingress of pitch from the pitch-chambers.

Having thus described my invention, I claim as new and desire to secure by Letters 100 Patent—

1. The combination, with a pitch-kettle, of a reservoir in the kettle and divided by a partition into compartments or chambers, a valve for each chamber, an air supply and discharge 110 pipe connected with the top of each chamber, a compressed-air pipe connected with said air-supply pipes, a four-way valve connecting the compressed-air pipe with the air supply and discharge pipes, said four-way valve being 115 provided with a port for the compressed air, a port for each air supply and discharge pipe, and a large outlet-port connecting with the atmosphere, while the plug of the four-way 120 valve is provided at one side with an enlarged portion and at the opposite side with a portion less in width than said large port, and means for conducting melted pitch from said reservoir to the barrel to be pitched, substantially as set forth.

2. The combination, with a pitch-kettle, of a reservoir or tank in the kettle, and divided by a partition into a number of compartments or chambers, a valve for each chamber, an air supply and discharge pipe connected with 125 the top of each chamber, a compressed-air pipe, an air-outlet pipe, a four-way valve connecting the compressed-air pipe with the air supply and discharge pipes, and with the pipe

leading to the atmosphere, the casing of the four-way valve being provided with ports for the compressed-air pipe, and for each air supply and discharge pipe, and a double port for the air-outlet pipe, means for setting the valve so as to supply either chamber with melted pitch, discharge the same, and reestablish atmospheric pressure therein, and means for conducting melted pitch to the barrel, substantially as set forth:

3. In a machine for pitching barrels, the combination, with a pitch-kettle for the melted pitch, and a tank or reservoir in the same, of means for admitting the pitch to said reservoir, an air supply and discharge pipe con-

necting the top of said reservoir with the atmosphere, and with the compressed-air pipe, a guard device located below the end of said air supply and discharge pipe, and a casing extending around the guard device and the end of said pipe so as to prevent the ingress of melted pitch into the air-pipe, substantially as set forth.

In testimony that I claim the foregoing as my invention I have signed my name in presence of two subscribing witnesses.

WM. L. MILLER.
